APPARATUS FOR CLEANING WELLS

Filed Oct. 5, 1942

FIG. 2.

Willis P. Orr. INVENTOR.

BY *J. G. McLean*
ATTORNEY

FIG. 1.

UNITED STATES PATENT OFFICE

2,397,199

APPARATUS FOR CLEANING WELLS

Willis P. Orr, Houston, Tex., assignor to Standard Oil Development Company, a corporation of Delaware

Application October 5, 1942, Serial No. 460,734

7 Claims. (Cl. 166—20)

The present invention is directed to apparatus adapted to aid in cleaning a well before producing through a screen.

In my co-pending application, Serial No. 460,733, filed October 5, 1942, now abandoned, a method of cleaning wells before producing through a screen is disclosed. The method therein disclosed involves blocking off of the screen and removing foreign bodies from the well by flowing well fluid through a by-pass at a relatively high velocity. After the cleaning step the by-pass is closed and the well then produced through the screen. As disclosed in the aforesaid application, a number of arrangements may be employed to carry out the procedure. The present application is directed to an embodiment useful for practicing the method claimed in my above mentioned application.

Other objects and advantages of the present invention may be seen from the following description taken with the drawing in which Figures 1 and 2 are elevations partly in section, Figure 1 showing the device adjusted to by-pass a screen and Figure 2 illustrating the device arranged for fluid flow through the screen.

The invention may be described briefly as including side ports arranged to by-pass a screen and a valve arranged at the upper end of the screen to close off the screen from the by-pass. The device is arranged so that after the well is cleaned manipulative steps performed by an operator at the surface will close the by-pass and open the valve to allow production through the screen into the tubing.

Turning now specifically to the drawing, the lower portion of a hole is disclosed with the lower end of casing 11 provided with a conventional cement plug 12. Within the casing and secured to a lower end of a string of tubing 13 for lowering into the bore hole is an assembly comprising screen 14, cylindrical member 15 secured thereto by suitable means such as collar 16 and a packer 17 secured to member 15.

A tubular member 10 is positioned within member 15 with member 10 having its lower end shaped to define an inwardly projecting circular ledge 19 and its upper end shaped to define an inwardly projecting circular ledge 28. Member 10 is fixed to member 15 by suitable means, such as welds 8 and 9, securing the lower and upper ends of member 10 to member 15.

Ledge 19 is provided with lefthand screw threads 20 which mate with similar threads on coupling member 21 attached to the lower end of tubing 13 and serve as a means of attaching

the assembly to the string of tubing. Spaced above collar 21 is another collar 22 carrying packer setting tool 23, the two collars being separated by a short joint of tubing 24. This joint of tubing is provided with a longitudinally extending slot 25.

Side port 26 pierces member 15 and member 10 secured thereto. A sleeve member 27 is slidably arranged within member 10 with its downward movement limited by member 19 and its upward movement limited by inwardly projecting ledge 28. Member 27 is provided with ports 29 to correspond with port 26 in members 15 and 10 and its upper end is provided with inwardly projecting ring 30 to which is attached inwardly extending shear pins 31. A groove 32 is provided in member 27 and a spring catch 33 is secured to member 10 immediately below ledge 28. Moving of member 27 to its upper position closes side ports 26, 29 and member 27 is locked in this position by the engagement of catch 33 in groove 32.

Circular ledge 18 is preferably constructed of metal and is arranged to carry a second smaller ring 34 which is preferably formed of readily breakable material such as commercial moldable resins. An elongated body which is shown in the drawing as rod 35 is provided at its lower end with plug 36 preferably of a readily deformable material such as rubber. The members 34 and 36 when arranged in the position illustrated in Figure 1 form a valve to close off the interior of screen 14 from communication with the interior of cylindrical member 15. The upper end of elongated body 35 may be provided with a spear head 37 for engagement with a conventional grappling tool or overshot. In addition the upper portion of the elongated body 35 is provided with a circular groove in which is arranged circumferentially movable annulus 38. Secured to annulus 38 by a shear pin 39 is a suitable member 40 arranged to project through slot 25. It is to be noted that shear pin 39 is constructed with a larger cross section than is pin 31 to insure that pin 31 will shear before pin 39.

In operating the device of the present invention, tubing 15 having attached thereto the assembly arranged as illustrated in Figure 1 is lowered into the bore hole until the liner is on bottom, or alternatively the liner may be hung in position by slips. The tubing may then be rotated to the right to disengage left hand threads 20 and the tubing raised enough to engage packer setting tool 23 with packer 17. The weight of the tubing is then allowed to rest on the packer

in an amount sufficient to operate it to seal the annular space between cylindrical member 15 and casing 11. The well is then allowed to flow through side ports 26, 29 to remove foreign material from the annular space defined by the screen and the bore hole and from the face of the producing formation.

After the well is cleaned the by-pass may be closed and flow through the screen initiated by either of the manipulative steps:

(1) An overshot on a wire line may be dropped inside the tubing to engage spear head 31. An upward pull on the wire line will first pull plug 36 out of member 34. Additional upward movement will engage member 40 with pin 31 to raise sleeve 21 to its uppermost position where it is located with side port 26 closed by member 21. An additional pull on the wire line will first shear pin 31, then pin 39 to release elongated body 35 so that it may be withdrawn to the surface leaving the inner portion of the tubing clear. The appearance of the device after this manipulation is completed is illustrated by Figure 2.

(2) If it is not desired to remove rod 35 from the bore hole, the device may be operated by manipulating tubing 13. An upward pull on the tubing will engage collar 21 with member 40 to withdraw plug 36 from member 34. An additional upward pull on the tubing will move sleeve 21 to its upward position to close port 26. When this operation is completed the tubing may be allowed to move downward to re-engage packer setting tool 23 with packer 17.

Having fully described and illustrated the present invention, what I desire to claim is:

1. A device adapted to be arranged in a bore hole comprising in combination a cylindrical member having side ports in an upper portion thereof, an inwardly projecting circular ledge secured to a lower portion of said member, a sleeve provided with ports corresponding to the ports of said cylindrical member slidably arranged in said cylindrical member, a shoulder secured to said cylindrical member limiting the downward movement of said sleeve, a second shoulder secured to said sleeve member limiting the upper movement of said sleeve, a plug arranged to cooperate with said inwardly projecting ledge to seal the lower end of said sleeve when in a first position and to allow flow through the opening defined by said ledge when in a second position, means adapted to be secured to a string of tubing for moving said sleeve from said first to said second position and said plug from said first to said second position.

2. A device in accordance with claim 1 in which the means for moving said sleeve includes a shear pin and said means for moving said plug includes a second shear pin.

3. A device in accordance with claim 1 including a rod attached to said plug, a spear head secured to said rod adapted to be engaged by a grappling tool, a member secured to the upper end of said rod by a shear pin and a shear pin attached to said sleeve for engagement with said member.

4. A device adapted to be arranged in a bore hole and to be attached to the upper end of a liner screen comprising, in combination, a cylindrical member provided with side ports, a sleeve arranged to expose the side ports when in a first

position and to close said ports when in a second position relative to said cylindrical member, a valve member arranged to close the lower end of said cylindrical member when in a first position and to allow fluid flow therethrough when in a second position relative to said cylindrical member, an elongated body arranged within the cylindrical member to assume a first position and a second position relative to said cylindrical member, a first means carried by said body arranged to engage and move said sleeve from its first to its second position as the body moves from its first to its second position and a second means carried by said body operatively connected with and arranged to move said valve member from its first to its second position as the body moves from its first towards its second position.

5. A device adapted to be arranged in a bore hole and to be attached to the upper end of a liner screen comprising, in combination, a cylindrical member provided with side ports, a packer body mounted on said cylindrical member above said ports, a sleeve member carried by said cylindrical member and arranged to expose said side ports when in a first position and to close said ports when in a second position relative to said cylindrical member, a valve member arranged to close the lower end of said cylindrical member when in a first position and to allow fluid flow therethrough when in a second position relative to said cylindrical member, a tubing member extending into the cylindrical member, readily disengageable means securing said tubing member to said cylindrical member, a body in the cylindrical member operatively connected to the valve member and arranged to move in the cylindrical member from a first to a second position and means secured to said body arranged to engage said sleeve member and to move the sleeve and valve members from their first to their second positions as the body moves from its first to its second position.

6. A device in accordance with claim 5 in which a packer setting means is mounted on said tubing.

7. A device adapted to be arranged in a bore hole and to be attached to the upper end of a liner screen comprising, in combination, a cylindrical member provided with valve ports, a sleeve member carried by said cylindrical member and arranged to expose the ports when in a first position and to close them when in a second position relative to said cylindrical member, a valve member arranged to close the lower end of said cylindrical member when in a first position and to allow fluid flow therethrough when in a second position relative to said cylindrical member, a tubing member extending into the cylindrical member and provided with readily disengageable means securing it to said cylindrical member, an elongated body arranged in the lower end of said tubing to move longitudinally therein from a first position to a second position and secured to said valve member to move it from its first to its second position as the elongated body is moved from its first to its second position, and means secured to said body arranged to engage with and move the sleeve member from its first to its second position as the body moves from its first to its second position.

WILLIS P. ORR.
